UNITED STATES PATENT OFFICE.

LEOPOLDO SUPERVIELLE BETANCOURT, OF HABANA, CUBA.

CLEANSING DEVICE FOR WATER-TUBE BOILERS.

1,369,774.

Specification of Letters Patent.

Patented Mar. 1, 1921.

Application filed November 13, 1918. Serial No. 282,331.

To all whom it may concern:

Be it known that I, LEOPOLDO SUPERVIELLE BETANCOURT, a citizen of the République of Cuba, and resident of Habana, Republic of Cuba, have invented certain new and useful improvements in Cleansing Devices for Water-Tube Boilers, of which the following is a specification.

This invention relates to devices for cleansing water tube boilers, especially to the cleansing device or mechanical blowing pipe forming the subject-matter of my co-pending application filed November 2nd, 1917, Serial No. 199,940 and its object is to provide certain improvements in said cleansing device with the aim of simplifying the construction of their various parts, thus aiding its mounting and operation, and thereby obtaining a more economical device.

Another object of the invention is to provide means connected with the cleansing device in the furnaces of the water tube boilers in order to protect such devices against the injurious action of the fire while same are inoperative or not working.

In the annexed drawings:

Figure 1 is a perspective view showing the cleansing device provided with the improvements forming the subject-matter of this invention.

Fig. 2 is a longitudinal vertical section showing the inside of the same device.

Fig. 3 is a detail showing in a front elevation the central part of the steam injecting tube.

Fig. 4 is an upper view of the cleansing device in operative position mounted through a wall of the boiler furnace.

Fig. 5 is an inner front view of the same cleansing device in operative position.

Fig. 6 is an upper view of the cleansing device in its inoperative position mounted through the wall of the boiler furnace.

And Fig. 7 is a partial outer front view of the furnace wall, through which the cleansing device is mounted.

This improved device comprises a horizontal cylindrical chamber 1 opened on both ends and provided at its bottom with an extension 2 having a double wing 3 for

securing same by means of screws 4 on the web of an I beam 5 scarfed in horizontal position in the lateral wall 6 of a furnace for a water tube boiler, through an opening 7 formed in said wall and lengthwise of which 55 opening said cylindrical chamber is placed. Said chamber has at a side and near its outer end an inlet 8 for supplying steam and that outer end is widened so as to form a packing box 8 within which a plurality of 60 leather washers 9 fit and which is closed by a threaded cover 10. These washers 8 and cover 10 are crossed at their center by a stem 11 having on its outer end a handle 12 arranged through a hole thereof on the reduced end of said stem and secured by a nut 13 which is threaded on said threaded end, and the inner end of said stem 11 is threaded in a tapering joint piece 14 which is provided with a plurality of side openings 15 and the portion of larger diameter of said piece 14 is threaded on the inner end of a cylindrical tube 16 concentric with respect to chamber 1 and with respect to stem 11 and extending through the other open 75 end of said chamber 1 and movable lengthwise through an opening in the inner end 17 of said chamber 1. On the outer end of said pipe 16 is threadedly mounted by one of its mouths the three mouth casing or 80 tubular T-shape joint 18, through the other two plain mouths of which is revolvably mounted the injecting tube 19 formed in a single piece and provided within said casing with two pairs of openings 20 and 21. 85 The portions of tube 19 that are outside of casing 18 are covered with metallic jacketing tubes 22 to protect the tube against the action of the fire, and in transverse holes extended in longitudinal line on the tube 19 90 and jacketing tubes 22 there are removably arranged the small nipples 23 which serve to discharge the jets of steam. These nipples are arranged in such a manner that one of them, indicated at 23' which is adjacent to 95 the plain lower mouth of casing 18, may strike during the rotary movement of tube 19 with a butt formed by a semicircular flange 18' projecting downward from the lower portion of casing 18 surrounding the 100

plain mouth and which is concentrical to tube 19. On this tube and immediately above the upper plain mouth is secured a beveled crown-gear 24 which meshes with a 5 beveled pinion 25 fixed on the end of a horizontal shaft 26 supported in a bearing formed in a bracket 25' projecting upward from the end of the casing 18 in which tube 16 is threaded and in another bearing 10 formed in an extension of handle 12. Said shaft 26 is provided at the outer end thereof with a hand-wheel 26' for its operation. The injecting tube 19 is closed at its ends by means of threaded caps 27.

15 Opening 7 of side wall 6 of the furnace wherein the cleansing device is lodged, is widened at the inner part of the wall and at a certain distance from the inner face of this wall are formed lateral recesses 28 for 20 receiving the half-doors 29, 30 which are vertically arranged for closing the opening 7 and are mounted on vertical shaft hinges 31 whose bolts are scarfed in the wall 7. Preferably the half-doors 29, 30 do not fit 25 close together, but to one of them is attached a covering plate 32 for effecting the closure. In this locked position, said half-doors 29, 30 are resting against the shoulders of said recesses 28 and these half- 30 doors are tied together by means of a loose transverse chain 33 connecting two eyebolts 34 fixed to the outer face of said half-doors and said chain passes through behind the injecting tube 19, whereby is provided an 35 automatic opening and closing for said half-doors. Opening 7 is closed on the inner side by means of a pair of vertical plates 35, 36 arranged in the same vertical plane and fitting at their edge in a small recess 40 provided in the outer face of wall 6, and said plates 35, 36 are connected together by means of two lateral lugs 37 and 38 laterally projecting from each plate and which are superposed two by two and are connected 45 by means of a screw 39, each plate presenting on its face a handle 40 and on the inner adjusting edge a semicircular notch 42 registering with each other so as to form a circular opening which serves as a passage 50 for the cylindrical chamber 1, and the notch 42 of the upper plate 35 is extended upward forming a vertical upward passage 43 which terminates in an arched-shaped passage 44, so as to allow the forward, backward, lateral 55 rocking motion of shaft 26.

In its inoperative position the cleansing device is placed partly within the narrow part of the opening 7 and partly outside of wall 6, and in communication with the furnace chamber by means of half-doors 29, 30. In these conditions, in order to operate the 60 cleansing device, the handle 12 is grasped with the hand and a pushing motion toward the interior of the opening 7 is im-

parted thereto whereby the injecting tube 19 in striking against the half-doors 29, 30, will push in same, thus separating them as much as required for giving passage to the same injecting tube 19, casing 18, and gears 24, 25, as it is shown in Fig. 4 of the drawings, the half-doors 29, 30 being held in that position by means of the transverse chain 33 connecting them. Then the injecting tube 19 is arranged in the proper inclined position by laterally rocking the handle 12, and in order to rotate the injecting tube 19 on the casing 18 to spread the steam jets to either side and between the water tubes 45 of the boiler, the hand lever 26' on shaft 26 which gives motion to the gears 24, 25 is caused to be rotated, the turning movement of tube 19 being limited by butt 18' against which the small nipple 23' strikes. Once the operation of the device has been completed, the handle 12 is pushed 80 backward, whereby the injecting tube 19 returns with the casing 18 and the annexed part of the device, passing first between the two half-doors 29, 30 until striking chain 33 and causing thus same to return carrying 90 with it the two half-doors 29, 30, until the small covering plate 32 may completely close the opening between the two half-doors, and thereby the opening 7 being completely closed, and the device protected 95 against the injurious action of the fire.

It is obvious that the form and arrangement of the doors and their connecting means with the cleansing device can be varied without altering the object of the invention, which is as claimed in the appended claims.

What I claim is:—

1. A cleansing device for water tube boilers comprising a chamber having means to admit fluid thereto, a tube mounted for longitudinal movement in said chamber and also for rotary movement, said tube projecting from the inner end of said chamber, an operating stem attached to the outer end of said tube, a T at the inner end of said tube, a blower header rotatably attached to said T, a lever attached to said stem, a shaft mounted in a bearing in said lever and also in a bearing on said T, said shaft being arranged 110 exteriorly of said chamber, and gears connecting said shaft and the blower header to enable the latter to be turned by said shaft.

2. A cleansing device for water tube boilers comprising a chamber having means to admit fluid thereto, a tube mounted for longitudinal movement in said chamber and also for rotary movement, said tube projecting from the inner end of said chamber, an operating stem attached to the outer end of said tube, a T at the inner end of said tube, a blower header rotatably attached to said T, a lever attached to said stem, a shaft mount-

ed in a bearing in said lever and also in a header, and means mounted on said chamber at the inner end thereof to coact with said lever and limit the extent of rocking movement of the blower header.

5 enable the latter to be turned by said shaft, said T and blower header having means to limit turning movement of the blower

In witness whereof I affix my signature.

LEOPOLDO SUPERVIELLE BETANCOURT.
